UNITED STATES PATENT OFFICE.

EMIL IMPENS, OF VOHWINKEL, GERMANY, ASSIGNOR TO WINTHROP CHEMICAL COMPANY, INC., OF NEW YORK, N. Y.

LAXATIVE.

No Drawing.

Application filed May 15, 1925. Serial No. 30,614.

It has been found that the laxative action of the 1.8-dihydroxyanthraquinone can be considerably increased by the admixture of a small amount of magnesium oxide 5 (MgO).

It is surprising that even a relatively small amount of this product suffices to considerably increase the laxative action. A mixture of 0.1 gram of 1.8-dihydroxyanthraquinone and 0.2 gram of magnesium oxide 10 has the same laxative action as doses of 0.2-0.3 gram of the 1.8-dihydroxyanthraquinone. This reduction of the doses is very important for the use of such laxatives for sensitive persons and it means saving costs in 15 veterinary medicine.

In order to illustrate my invention more fully, I give the following example:-

Example.-100 parts by weight of 1.8-

dihydroxyanthraquinone are ground together with 200 parts by weight of magnesium oxide and from this mixture tablets are pressed. The yellowish white tablets assume a red coloration, caused by the formation of the magnesium lake. 20

I claim:-

1. The process for preparing laxatives, which process consists in mixing 1.8-dihydroxyanthraquinone with magnesium oxide.

2. As a new article of manufacture a laxative being a mixture of 1.8-dihydroxyanthraquinone with magnesium oxide. 30

3. As a new article of manufacture a laxative tablet comprising 1.8-dihydroxyanthraquinone and magnesium oxide. 35

In testimony whereof I have hereunto set my hand.

EMIL IMPENS.
